(57) **CLAIM**

The ornamental design for a connector with a shutter for photoelectric conversion, as shown and described.

DESCRIPTION

FIG. 1 is a front elevation view of a connector with a shutter for photoelectric conversion showing our new design; FIG. 2 is a rear elevation view thereof; FIG. 3 is a top plan view thereof; FIG. 4 is a bottom plan view thereof; FIG. 5 is a left side view thereof; FIG. 6 is a right side view thereof; FIG. 7 is a left side view thereof in the position wherein a shutter is entirely opened; and, FIG. 8 is a left side view thereof in the position wherein a shutter is half opened.
